UNITED STATES PATENT OFFICE.

GLEN ELGIN KEEFER, OF WESTPORT, CONNECTICUT, ASSIGNOR TO CHARLES H. KEMPER COMPANY, OF WESTPORT, CONNECTICUT, A CORPORATION OF CONNECTICUT.

FUSE.

Application filed November 21, 1919. Serial No. 339,654.

To all whom it may concern:

Be it known that I, GLEN ELGIN KEEFER, a citizen of the United States of America, residing at Westport, in the county of Fairfield and State of Connecticut, have invented certain new and useful Improvements in Fuses, of which the following is a specification.

My invention relates to fuses, and particularly to cartridge fuses of the renewable fuse link type, the object of my invention being to provide an improved construction which is economical to manufacture, simple to operate, and safe in service.

15 In the accompanying drawings—

Fig. 1 is a broken side elevation of a fuse in which my invention is embodied in one form;

20 Fig. 2 is an end elevation thereof, partially broken away;

Fig. 3 is a plan of the gas screen;

25 Fig. 4 is an end view with the blade contact and cap removed;

Fig. 5 is an end elevation showing the bridge opened to permit access to the interior of the fuse body for the renewal of the fuse;

30 Fig. 6 is a longitudinal section through a fuse of different type;

Fig. 7 is an end elevation thereof;

Fig. 8 is an end elevation with the cap removed;

Fig. 9 is a view similar to Fig. 5; and

Fig. 10 is a plan of the screen.

35 Fig. 11 is a perspective of a fuse showing the parts at one end detached and in position for assembly;

Fig. 12 is an end view illustrating the shutter partially closed; and

40 Fig. 13 is a perspective of the fuse element alone.

In the construction shown in Figs. 1 to 5, the present fuse comprises a tubular cartridge body 15 of fiber, or other suitable insulating material, which serves to house the renewable fuse link 16 passing longitudinally therethrough. At each end of the body a metallic ferrule 17 is secured in any suitable manner, as, for example, by crimping at 18, where a permanent connection is desired. This ferrule 17 has an end opening 19 which affords access to the interior of the fuse chamber to clean out the latter and to facilitate the replacement of a blown fuse link. At one margin of the opening 19

a rectangular way 20 is cut, through which the fuse link passes.

Normally closing the opening 19 is a bridge plate 21 freely pivoted on the pin 22 carried by the ferrule 17. A second pin 23, 60 also carried by the ferrule, serves as a stop, which is engaged by the nose 24 of the bridge plate when the latter is swung into closed position, as shown in Fig. 4. It will be noted that in this position the fuse 16 is 65 closely confined in the way 20 and substantially fills the latter. The bridge plate 21 is marginally notched at 25 to permit the reduced end 26 of the fuse link to be carried back in the channel 27 formed in the threaded area 28 of the outer end of the ferrule 18. 70

Each blade terminal 29 of the fuse is carried by a base plate 30, perforated at 31 to freely engage the studs 22 and 23 which project beyond the bridge plate 21 and serve 75 to maintain the blades 29 in alignment at opposite ends of the fuse. In order to prevent escape of flame when the fuse is blown, a baffling and cooling screen 32, slotted at 33, is pressed down over the blade 29 and 80 rests upon the outer face of its base plate 30. The parts are rigidly united and contact is established between the fuse link and the base plate 30 of the blade 29 by means of the draw-up screw cap 34, which engages the 85 threaded area 28 of the ferrule 17. The holding flange 35 of the cap overlies the marginal area of the screen 32 and base plate 30, leaving open the area overlying the perforations 31 to permit the free escape of 90 the gas through the screen on the blowing of the fuse.

It will be noted that when the cap 34 is screwed on the ferrule, and the parts are clamped rigidly together, its skirt 36 holds 95 down the bent-over end 26 of the fuse link, but does not wholly conceal the latter, thus leaving an exposed end 37, on which may be stamped the rated capacity of the link. It will also be noted that in the assembled position of the parts an expansion chamber 38 is 100 afforded between the outer face of the bridge plate 21 and the inner face of the base plate 30 of the terminal 29. From this chamber the gases are free to escape through the holes 31 in the base plate 30 and the screen 32, while a restricted passageway is also afforded by the loose fit of the cooperating threaded areas of the ferrule and screw cap at 28. The passage 27 is baffled by the corrugated 105 110

gations 18, and by crimps in the end of the fuse link, if desired.

The construction shown in Figs. 6 to 10 differs from that just described, principally in such obvious modifications as are incidental to the adaptation of the same ideas to a cartridge fuse of the clip type. As in the first construction, this modification comprises an insulating body 15 having at each end a ferrule 17 crimped at 18 into permanent engagement therewith, and having an exterior threaded area 28 at its outer end. The bridge plate 21 is pivoted to the ferrule 17 by the stud 22 and is halted by the stud 23 in closed position. It is also provided with a notch 25, which registers with the notch 27 in the ferrule, to permit the fuse 16 to be carried over the bridge plate and turned down in the channel 27 beneath the screw cap 39. The latter is provided with an end closure diaphragm 40 integral with the cap, but perforated at 41 to permit the escape of gases therethrough. Within the cap is a screen 42 which rests directly upon the bent-over fuse end and establishes good electrical connection between the parts when the cap is screwed on the ferrule 17. In this construction, as in that first described, an expansion chamber 38 is afforded for the gases emerging from the fuse chamber, while the screen 42 prevents the escape of flame through the holes 41. The bent-over end of the fuse is carried beyond the skirt of the cap 39, and the rating of the fuse is indicated upon the exposed end 37 thereof.

The construction shown has several features of marked value. It will be noted that when the screw cap 34 is turned down hard, the bridge plate 21 is forced firmly against the end face of the ferrule 17 and forms a substantial seal therewith. The fuse chamber is therefore practically closed except at the fuse passage 20, and this passage is substantially filled by the fuse itself. The channels of escape for the gas are quite restricted therefore, and sufficient pressure is maintained in the chamber to smother at once the arc which tends to form on the blowing of the fuse. On the other hand, such gas as does escape passes into the expansion chamber 38, where it is somewhat cooled before it passes out through the vents 31 or 41, while any flame is obstructed by the screen 32 or 42. This construction makes it possible to carry out the capacity indicating end of the fuse to exposed position on the exterior of the fuse body, since the expansion chamber and its end vents take care of the flame, and the latter has no tendency to blow out at the channel 26. Moreover, the corrugations at 18 tend to baffle the passage of gas at this point, an effect which may be heightened by crimping the fuse also at this point. So far as I am aware, no cartridge fuse of the renewable type has heretofore been made in

which the rating end of the fuse link can be carried out of the fuse chamber and exposed with impunity on the exterior of the fuse body. This is a feature of great practical value as an added safeguard against improper fuse installations, not only because inspection is easy, but also because it remains an uninjured telltale when the fuse is blown and responsibility for damage caused is to be traced.

The construction shown is simple and rugged, easy to manufacture and assemble. Obviously, however, the details of construction may be variously modified to attain the same end without departing from what I claim as my invention. My underlying thought is to provide a vented expansion chamber communicating with the substantially sealed fuse chamber and provided with means to prevent the escape of flame. The end vents are screened. The side vent through the indicating tab channel is baffled. The vent through the threads of the ferrule and cap is circuitous and prolonged, but in any case the vents from the expansion chamber, in which the gases are somewhat chilled, are sufficient to maintain this chamber at a pressure very much lower than that which exists in the fuse chamber.

I claim—

1. A cartridge fuse having a fuse chamber, a bridge piece pivotally secured at one end thereof, a fuse link passing from the fuse chamber and bent at one end over said bridge piece in assembled position, a member bearing upon said bent-over fuse end and spaced thereby from the pivoted bridge piece to afford an expansion chamber, means for clamping said member upon the fuse end, and means affording an end vent for the gases generated by the melting of the fuse link in the fuse chamber.

2. A cartridge fuse having a fuse chamber, a bridge piece pivotally secured at one end thereof, a fuse link extending from the fuse chamber and bent over said bridge piece in assembled position, a member bearing upon the bent-over end of said fuse link and spaced thereby from the pivoted bridge piece to afford an expansion chamber, said member lying in the path of escape of the gases from the fuse chamber and causing the same to change direction, and an end vent for the escape of said gases generated by the melting of the fuse link in the fuse chamber.

3. A cartridge fuse comprising a chambered fuse body, a ferrule affixed to the end of said body, a closure member pivoted on the end of said ferrule and closing the latter save for the fuse passageway, a fuse link arranged in the fuse chamber and extending therefrom through said passageway and having its end bent over said pivoted member in assembled position, a clamping mem-

ber bearing on the bent-over end of the fuse and forming with said pivoted closure member an expansion chamber communicating through the fuse passageway with the fuse chamber, said clamping member obstructing the direct flow of gases from said passageway and causing the same to change direction, together with means for venting the gases at the end of the fuse.

4. In a cartridge fuse, a fuse chamber, an end closure therefor, a fuse extending from the fuse chamber adjacent the margin of said end closure, the end of the fuse link extending across said closure member to exposed position on the exterior of the fuse chamber, a baffling member bearing on the bent-over end of the fuse link, and means for clamping said baffling member in position, together with a vent for the gases, said vent being located at the end of the fuse at a point remote from the exposed end of the fuse link.

5. In a cartridge fuse, a tubular insulating casing, affording a fuse chamber, a metallic ferrule secured at one end of said ferrule, and a bridge piece pivoted on said ferrule and affording a support over which one end of the fuse link may be bent.

6. In a cartridge fuse, a tubular insulating casing affording a fuse chamber, a metallic ferrule secured at one end of the chamber and having a diaphragm which affords a partial end closure for the fuse chamber, a bridge piece pivoted on said diaphragm and co-operating therewith to close the end of the fuse chamber, save for the fuse passageway, in combination with a fuse link arranged in said fuse chamber and extending therefrom between adjacent margins of the bridge piece and diaphragm, said link having an offset end overlying the bridge piece, and a baffling member bearing on said offset end of the fuse link and obstructing the free passage of gases from the fuse chamber through the fuse passageway, together with an end vent for the fuse chamber.

7. As an end element of a cartridge fuse, a metallic ferrule adapted to be secured to

the end of the fuse body, said ferrule having a partial end closure diaphragm for the fuse chamber but affording an opening through which access to the fuse chamber may be had, together with a shutter pivoted on said end closure diaphragm serving to complete the closure of the end opening in the ferrule except for a fuse passageway therethrough.

8. A cartridge fuse having a tubular body of insulating material, a ferrule permanently affixed thereto and forming a partial end closure with central opening to afford access to the fuse chamber, and through which the end of the fuse is passed, a bridge piece pivoted thereon and normally closing said central opening except for the fuse passageway, and across which the fuse end is angled in the assembled fitting, in combination with a cooperating closure member clamping said angled-over end of the fuse and spaced thereby from the bridge piece to afford an expansion chamber, said closure member being apertured to afford an end vent for the fuse.

9. A cartridge fuse having a tubular body of insulating material, an exteriorly channeled ferrule permanently affixed thereto and forming a partial end closure with central opening to afford access to the fuse chamber and through which the end of the fuse is passed, a bridge piece pivoted thereon and normally closing said central opening except for the fuse passageway, and across which the fuse end is angled and bent back through said ferrule channel to exposed position on the exterior of the fuse body, in combination with a screw-clamped end closure bearing on said angled-over fuse end and spaced thereby from the bridge piece to afford an expansion chamber, said closure member being apertured to afford an end vent for the fuse, and the screw clamped end closure engaging the threaded area of the ferrule.

In testimony whereof I have signed my name to this specification.

GLEN ELGIN KEEFER.
